UNITED STATES PATENT OFFICE

2,581,801

MULTIPLY BAG TUBING MACHINE

Marcel Lienart, Brussels, Belgium, assignor to St. Regis Paper Company, New York, N. Y., a corporation of New York

Application June 18, 1948, Serial No. 33,768

14 Claims. (Cl. 93—63)

1

This invention pertains to improvements in bag tubing machines for making multiwall paper tubes, in bag lengths, for the production of multiwall paper bags therefrom. The invention pertains to machines of this type especially adapted for making multiwall tubes for so-called stepped-end bags, to be subsequently formed into the finished bags on a bottoming machine.

The invention will be described with reference to a machine so constructed and adjusted as to manufacture a stepped-end bag tube similar to that disclosed in the United States Patent to Hoppe No. 2,055,030, granted September 22, 1936, but having as many as five plies, three of which have their end portions formed to present the relatively stepped-end relationship as shown in that patent, the remaining two plies respectively (one or both of which may be omitted if a four or three ply bag is desired) being of a configuration such as to duplicate two of the others and with their end edges coterminous therewith. In other words the bag end edges will have three steps formed of three of the plies, two of which are duplicated by the remaining two plies so that two of the plies do not present individual stepped ends. It will be understood, however, that the machine here disclosed may be set up and adjusted for making other forms of stepped-end bags, and in fact the machine is also adapted for making multiwall bag tubes of various types which do not have stepped ends.

The problem of constructing an automatic machine for forming multiwall stepped-end bag tubes presents a number of complications and difficulties. Since there are several web ends to be separated along lines which are not coterminous, the usual practice for non-stepped-end bag tubes cannot be followed of cutting off the formed multiply tube at bag length intervals by a simple rotating cutting knife. Instead it has been heretofore proposed first to perforate the webs individually across their width, then superpose the several webs with the perforations in stepped relationship, then to form the webs into a tube, and finally to pull the tube apart into bag lengths at the stepped lines of perforation. While this procedure may be followed with relatively slow-operating tubing machines, it involves several difficulties. For example, for relatively large bags, particularly if made at high

2

speed, the webs will tend to tear apart at the lines of perforation as they are being pulled through the tuber, or else the perforations must be so slight that ultimate separation of the bag lengths is difficult without tearing. Also, in order to provide side and end flaps of proper relative lengths and relationship in the finished stepped-end bag, it is desirable to provide slits separating the side and end flaps of each web, and it has heretofore been proposed to accomplish this slitting as an initial step performed concurrently with the forming of the perforations. Yet this involves a multiplicity of separate slitters for a multi-ply bag, all of which must be separately adjusted or replaced every time the machine is readjusted to make a bag tube of different dimensions. Furthermore, such individual slitting of the webs involves the difficulties of maintaining accurate and proper register of the slits in the numerous webs after being superposed, or else the flaps of the bag bottom when finished will not fit properly or be capable of being glued and sealed properly.

With the stepped-end construction of the above-mentioned Hoppe patent, the webs in separated condition may at first be individually perforated part way across the web only, viz. at the parts which are to form the middle stepped-end portions of the tube, whereas the portions which are to form the sides of the tube (that is, the end flap portions at the bottom of the finished bag) may be left unperforated and not cut until after the tube is formed in the tuber, thus leaving the webs in strong condition, capable of being pulled rapidly through the machine without danger of separation at the perforations, even though the perforations may have been so effectively made as to weaken or sever the greater part of the fibre along the middle portion of the end edge of the bag. Then, just before the tube is to be separated into bag lengths, the necessary longitudinal slits may be formed simultaneously through all of the plies of the bag, and hence in accurate register, by the use of a single pair of slitting devices, and the side portions of the tube may be cut by a single pair of transverse knife portions. At this stage the pulling apart of the tube into bag lengths may be accomplished very easily and without any danger of tearing, even with the machine running at high speed, since

it is only necessary to pull the tube lengths apart along relatively weak lines of perforation across the middle portion of the bag ends. But despite the general advantages of making stepped-end bags according to the above-mentioned Hoppe patent, the construction of a commercially practical machine for automatically carrying out this method involves additional serious difficulties, particularly since the perforating must be done before the tubing operation, and the slitting and final cutting at the edges of the tube must be done at a widely spaced position after the webs are assembled and formed into a tube, yet along lines which are maintained in accurate register with the positions of the perforations in the several plies. And if, as is ordinarily necessary for practical purposes, the machine must be adapted for making bags of various dimensions, the necessary adjustments for so doing while still maintaining accurate register and positioning of the lines of gluing, perforation, slitting and cutting and the proper timing of the various moving parts, presents problems which others have not satisfactorily solved, but which are overcome by the present invention even to a degree whereby stepped-end tubes may be accurately formed more rapidly than multiwall bag tubes of other types have heretofore been made and with little loss of time for readjustments of the machine to different bag tube dimensions.

In accordance with the invention, the machine is so constructed that various registry adjustments for the necessary perforating, slitting and cutting operations on the paper webs, and for the degree or extent of stepping or overlapping of the successive plies at the bag ends, can be made from a single control position, and while the machine is either stationary or running, by simple manipulation of hand wheels or clutch controls. Also, registry adjustments can be made, in similar fashion, as between the regions of perforating, cutting, slitting and gluing, on the one hand, and any printed matter impressed on the outer paper web for appropriately centering the latter on the finished bags.

In the bag tuber machine of the invention, the various paper webs forming the bag plies are fed from rolls thereof, either singly or in superimposed pairs, through perforator and glue applicator units individual to such single webs or superimposed web pairs, wherein said webs or pairs are transversely perforated and certain of them printed with transverse glue patterns for subsequently gluing the successive webs together. The webs are fed from these perforator and gluing units in spaced-apart relation over a series of guide rolls individual thereto, and then over rolls at which the webs are assembled in proper superposed relation, the positions of and spacings between the latter rolls being adjustable, individually or in pairs or groups, for adjusting the spacings longitudinally of the webs between the lines of perforations of the successive webs, the webs being also fed over these rolls in laterally staggered or stepped relation, thereby to produce in the finished multiwall bag tube, a stepped, longitudinal seam formed by the successive plies, and also a stepped end configuration for the individual bag tubes when subsequently cut and separated into bag lengths. After passing over the adjustable assembly rolls, the webs are superimposed in the laterally stepped relation aforesaid, and are fed thence past a glue-applicator unit which applies longitudinally extending glue lines along the laterally stepped

edges, but the glue lines being interrupted at each perforated line. The webs are fed thence through a tube-forming unit which forms the webs into a continuous tube, each ply of which is glued to itself along the longitudinal seams formed by the stepped, lateral edges. From this point the continuous multiwall tube may pass through a slitter which appropriately slits the tube longitudinally at bag lengths adjacent the opposite edges thereof, and in the regions of the transverse perforations therein, the tube passing thence through a cutter which cuts the tube into bag lengths adjacent its lateral edges, and separates the successive plies thereof along the lines of perforations therein, thereby to produce multiwall tubes of bag length, the successive plies of which are glued to each other by the transverse glue lines, the said tubes having ends appropriately stepped and slit for subsequent forming into stepped end bags on a bottoming machine.

Referring to the drawings:

Figs. 1, 1a and 1b comprise a view in side elevation, and partly in longitudinal section, of a multiwall bag tubing machine in accordance with a preferred modification of the invention, Fig. 1a being a continuation of Fig. 1 as taken along a—a of Fig. 1; while Fig. 1b is a continuation of Fig. 1a as taken along the line b—b of Fig. 1a.

Fig. 2 is a plan view of the portion of Figs. 1 and 1a located between the lines c—c and d—d thereof; while Fig. 2a is a plan view of the portion of Figs. 1a and 1b, located between the lines d—d and e—e thereof.

Fig. 3 is an enlarged vertical cross section of one of the perforator and glue applicator units, as taken at 3—3 of Fig. 2, this assembly perforating the paper plies transversely at bag lengths and applying transverse glue lines to certain of the plies. Fig. 4 is a vertical section taken at line 4—4 of Fig. 3, illustrating the glue applicator construction and drive; while Fig. 5 is a vertical section taken at 5—5 of Fig. 3, showing certain pull rolls and drive therefor. Fig. 6 is a horizontal sectional detail, as taken at 6—6 of Fig. 4, showing more of the drive. Fig. 7 is a vertical section of the perforator as taken at 7—7 of Fig. 3. Fig. 8 is an end view of the drive gear and dial for angularly adjusting the perforating roll assembly. Fig. 9 is a vertical section, taken at 9—9 of Fig. 3, showing more of the drive; while Fig. 10 is a section as taken at 10—10 of Fig. 3, showing more of the glue applicator mechanism.

Fig. 11 is an enlarged sectional view of the middle portion of the perforator drum assembly as illustrated in transverse section in Fig. 3 and in elevation in Fig. 7; while Fig. 11a is a sectional view taken along line 11a—11a of Fig. 11; Fig. 12 is an enlarged elevational view of portions of the rotatable perforator knife construction and parts for supporting and adjusting same, Fig. 12a being a sectional view taken along line 12a—12a of Fig. 12, and Fig. 13 being taken approximately at 13—13 of Fig. 12.

Fig. 14 is an enlarged end elevation of that portion of Figs. 1a and 2 which is located between the lines f—f and d—d, and comprising web assembly rolls and glue applicator assembly for superimposing the paper plies and gluing longitudinal edges thereof. Fig. 15 is an enlarged vertical section as taken at 15—15 of Fig. 14, illustrating the glue applicator mechanism of Fig. 14; while Fig. 16 is a sectional elevation of the guide roll assembly as taken at 16—16 of Fig. 14. Fig. 17 is an enlarged end elevation

detail of Fig. 14. Fig. 18 is an enlarged cross-sectional detail taken at 18-18 of Fig. 16. Figs. 19, 20 and 21 are fragmentary views in elevation of a shaft-actuated clutch mechanism employed in the Fig. 14 assembly for selectively adjusting the spacings between the rolls of Fig. 14. Fig. 22 is an enlarged cross section of the glue applicator as taken at 22-22 of Fig. 15; while Fig. 23 is a cross section of the glue applicator as taken at 23-23 of Fig. 22.

Fig. 24 is a longitudinal sectional elevation of the main pull roll, slitter and bag length cut-off mechanism as taken at 24-24 of Fig. 2a (some details being omitted for clearness); while Fig. 25 is a plan view of Fig. 24, with parts omitted to illustrate the operation of this portion of the apparatus. Fig. 25a is an enlarged detail view taken at 25a-25a of Fig. 25 and showing certain parts of one of the slitting devices.

Figs. 26 and 27 comprise a diagrammatic showing, mostly in plan view, of the overall drive for the complete machine, the latter as illustrated in Figs. 1 to 1b inclusive, Fig. 27 being a continuation of Fig. 26 as taken along the line g-g thereof.

Figs. 28 to 31 inclusive, are plan views of the progressive stages in the development of the multiwall bag tube as produced on the machine of Figs. 1 to 27 inclusive; while Fig. 32 is a plan view illustrating the first step in the bottoming operation for forming the finished bag, as carried out on a bottoming machine, the latter not shown or included as part of the present invention.

Referring to Figs. 1 to 2a inclusive, and considering first the overall operation, as above stated the tuber machine is illustrated as set up to make a five-ply bag tube, the various paper plies 10 to 14 inclusive of which are fed respectively from paper rolls 15 to 19 inclusive, individually mounted on roll stands as at 20, 21, each of which includes conventional facilities as indicated for shifting a new roll of paper into place as the paper becomes all used from the previous roll. For maintaining appropriate back tension on the paper webs, a belt 22 of canvas or the like, having one end secured to a cross-walk 23 is looped over the roll and terminates at a weight 24. Each web, such as 14, in passing off the paper roll, such as 19, is fed under a guide roll as at 25, and thence over a resiliently mounted guide roll as at 26, from whence it is fed under the guide roll for the next web, as at 27, whereby the two webs are superimposed, this procedure continuing for the successive webs until all five webs are superimposed in passing under the final guide roll 28, the rolls of paper being so positioned in the roll stands that the webs are fed in transversely stepped relation, as at 29, Fig. 2, at which point the uppermost web 10 is separated from the rest, passing over guide roll 29', the remaining webs 11-14 inclusive passing under this roll. From this point, the upper web 10 passes under a guide roll 30 in a perforating and glue-printing unit, shown generally at A, and thence respectively over and under a pair of driven pull rolls 31; while the next lower web 11 passes under a guide roll 32 of unit A and thence respectively over and under a pair of driven pull rolls 33, from whence webs 10 and 11 are guided under and over appropriately disposed guide rolls into superimposed relation at 34.

The purpose of bringing the webs 10 and 11 together at 34 is in order concurrently and identically to perforate them at bag length intervals in a perforator 35, in the manner illustrated at

5 36 and 37 in Fig. 28, wherein the distance 38 represents one bag length, the upper web 10 being torn away to show the perforations 37 in the next lower web 11 corresponding to the perforations 36 in the upper web 10. After passing through the perforator 35, the webs are again separated by means of the guide rolls 36', web 10 passing downwardly and thence upwardly under appropriately disposed guide rolls, as at 37', 10 while web 11 passes upwardly over guide rolls, as at 38', and thence through a glue-printing device 39. In passing through the device 39, the web 11 has printed on its surface which is to face web 10, a glue pattern such for example as shown 15 at 40 in Fig. 28, and for purposes described hereinafter.

In similar fashion the intermediate webs 12 and 13 are fed into the next adjacent perforating and glue-printing unit, shown generally at B, the upper web 12 passing therein under a guide roll 41, thence through a pull roll stand 42; while the lower web 13 passes similarly under a guide roll 43 and through a pull roll stand 44, the webs passing thence under and over appropriate guide rolls into superimposed relation at 45, where they are concurrently and similarly perforated by a perforator 46, to perforate the same as shown at 47 and 48 of Fig. 28, for webs 12 and 13, respectively. In passing out of the perforator 46 the webs are separated by means of guide rolls 49, web 12 passing thence downwardly past a glue applicator 50, for printing a glue pattern on its normally upper surface as shown at 51 of Fig. 28, the web passing thence upwardly over a guide roll 52; while web 13 passes upwardly over guide rolls as at 53, and past a glue applicator 54, for printing on its normally upper surface a glue pattern as shown at 55, Fig. 28, the web passing thence up over a guide roll 56.

40 In similar fashion, the lowermost web 14 is fed into the final perforating and gluing unit, shown generally at C, wherein it is fed under a guide roll 57 and over various other guide rolls, as at 58, thence through a pull roll stand 59 and over appropriate guide rolls through a perforator 60, wherein it is perforated as shown at 61, Fig. 28, the web passing thence past a glue applicator 62, wherein a glue pattern is printed thereon as shown at 63, Fig. 28, the web passing thence out 50 over guide rolls, as at 64.

If desired the lower surface of the lower web 14 may carry printed matter such as trade names or descriptive matter which is to appear on the outside of each bag tube. Such printing may be 55 done on a roll of the paper before it is mounted on the stand 19, or if desired the paper from stand 19 may be run through a printing press on its way to the tubing machine here disclosed. In either event it is of course necessary that the 60 printing on each bag tube be at a predetermined location with respect to the lines of perforation, and the rollers at 58 provide a ready means for suitably adjusting the longitudinal position of the printed matter on web 14 with respect to the 65 perforating, which is done at the perforator 60. That is, a roller 58a may be suitably mounted on a vertically adjustable member 58b, vertically 70 slideable as by a hand wheel 58c to thus increase or shorten the loop of paper passing over the roller 58a to the extent necessary for the above indicated purposes. However, the adjustable roll means at 58, although a convenience in first setting up the machine to a given bag length, is not essential, since a further means in the form

75 of a "compensator" (hereinafter described) is

provided and may be used to adjust the position of the printed matter on the bag tubes within close limits while the machine is running.

From the perforator and glue applicator units A to C inclusive, webs 10 to 14 inclusive are fed in spaced-apart relation, as shown, to a web assembling and longitudinal seam gluing unit shown generally at D, and referred to herein for convenience as the "pagoda." The webs are fed into the unit D over spaced-apart guide rolls individual thereto as at 64, these rolls being mounted on an inclined supporting frame 65, and from these rolls the webs are fed all in a correspondingly inclined direction and in superimposed relation through a glue applicator 66, which prints along the downwardly exposed, stepped edges 29a, Fig. 2, of the successive paper plies, glue lines as shown at 67 of Fig. 29, this view also showing the various plies of Fig. 28 as superimposed on the pagoda D and glued together by the transverse glue lines 40, 51, 55, 63 (Fig. 28).

From the glue applicator 66, the superimposed webs are now fed, as at 68, into a tubing unit for folding the lateral edges of the plies over into a tube, with the glue lines 67 forming longitudinal seams, respectively, in the manner illustrated at 67a (Fig. 30), the unit E being of a suitable known construction for shaping the webs into a tube, and being followed by driven pull rolls 71.

It will be noted that the roller 64 and the glue applicator 66 permit the webs to travel at an angle to the vertical and on down to the tube forming device, without any substantial change of direction from the point where the webs are superposed, and until the starting of the folding over of the webs in the unit E, and that the superposed webs pass into the unit E at an angle in the neighborhood of 45° to the vertical. It has been found that this arrangement is such that any tendency of the webs to come apart at the perforations is eliminated at these regions. On the other hand, if the webs after being superposed and glued together, should be carried around a substantial part of the periphery of any roller, the differences in tension between the inner and outer webs tends to cause separation of the tube lengths at the perforations. Also, if the angle at which the webs pass into the tube forming unit varies by more than about 5°, for example, either way from the 45° shown, the same difficulty may arise.

The thus-formed multi-ply bag tube is now fed through a slitter 72 for longitudinally slitting the bag tube at successive bag lengths and near the opposite sides thereof, as shown at 73 and 74, Fig. 30, the tube passing thence under a cutter 75 for transversely cutting the tube at bag lengths from the longitudinal slits 73, 74 outwardly, as shown at 76 and 77, Fig. 31. Concurrently with the cutting operation, the tube is separated into bag lengths by pull rolls 78 and 79, mounted respectively on the entry and exit sides of the cutter, and so driven that the exit rolls 79 run at a somewhat higher peripheral speed than the entry rolls 78, thereby to separate the tube into bag lengths along the lines of transverse cutting and perforation thereof, and as illustrated at 76, 77, 80 of Fig. 31. The so-formed bag tubes then pass onto discharge and conveyor units which may be of conventional construction and are now ready for the bottoming operation, as partially indicated at 81, Fig. 32, but forming no part of the present invention.

Referring now to the detailed construction of

the various pieces of apparatus above referred to, the perforator and glue applicator units A, B and C, are all constructed in generally similar fashion, with the exception that the first unit 5 A contains only one glue applicator 39, while the second unit B contains two glue applicators 50 and 54, and the last unit C contains but one glue applicator 62. Accordingly, a detailed description of but one perforator and glue applicator assembly will be required, namely that of unit B, Fig. 1a, shown in detail in Figs. 3-13 inclusive.

It will be noted that the series of units A, B and C are located in spaced-apart relation so that there is a passageway available on each side of each unit affording easy access by the operator to the perforating mechanisms 35, 46 and 60 as well as to each of the gluing devices, without dismantling any of the equipment. Also with this arrangement of the perforating and gluing units, one or more additional similar units may be provided, if desired, for the manufacture of six or seven ply bag tubes, or in case the machine is to be used only for three or four ply bag tubes, one of the units shown may be readily omitted with a saving of space and without modification of the mechanisms of the other units.

In Fig. 3 the pair of paper webs passing through the unit are designated generally as W1 and W2, in order that the following description will apply to any and all of the units A, B and C. In these figures the perforator, designated generally by the numeral 93, comprises a transversely-extending, stationary perforator bar 91, serrated or toothed along its upper edge, as shown at 92 (Fig. 11) and a co-acting, driven perforator roll 93, having mounted thereon a series of three beveled cutter bars 94, 95, 96, the beveled edges of which sweep across the serrated edge 92 of the stationary perforator bar 91, thereby to perforate the paper plies in the manner illustrated in Fig. 28, as the moving cutter bars sweep across the stationary bar. The rotary member 93 rotates once for each bag length of paper webs fed therethrough, and is, moreover, driven at such speed that the cutting edges of the rotary cutter bars 94-96 travel at a greater circumferential speed than the linear speed of the paper webs W1, W2, passing through the perforator. As hereinafter explained more fully, while the rotary cutter blade 93 is always driven at the rate of one revolution per bag length, the linear speed of the paper webs is varied depending upon the desired length of the bag tube being formed. Assuming that the machine is constructed to form bag tubes of different lengths varying from some 20 inches up to 48 inches, for example, then to permit the perforating knives always to travel at a greater speed than the paper webs, the rotary member 93 may be made with a circumference at the cutting edges, for example of about 54 inches. As will be noted from Figs. 7 and 12, the rotatable cutter bars 94-96 are so adjusted that their cutting edges will be at a slight angle with respect to the stationary bar 91, so that the perforation apertures will be formed in succession across the webs with a shearing effect, and since the rotatable blade edges are always moved at a speed faster than the webs, this shearing effect will take place without tearing and without any objectionable variation in the widths of the perforation apertures in a direction longitudinally of the webs, despite variations in the web speed for different bag lengths. Hence it is unnecessary to vary the speed or radius of the per-

forating knives upon adjusting the machine to various bag lengths.

The stationary cutter bar 94 is adjustably mounted on a supporting structure 97, by means of set screws 98 passing through slots 99 in the cutter bar for permitting adjustment thereof, vertical adjustment of the bar being additionally effected by means of vertical adjusting screws 100, threading into the supporting structure 97.

Referring to Figs. 7 and 11-13 in further detail, the middle cutter bar 94 is mounted on a blade holder 101 having three slotted lug portions 102 on its upper side adapted to be bolted as indicated in circumferentially adjustable position on the rotary member 93, there being four similar slotted lugs 103 along the lower side of the member 101 adapted to be similarly bolted in adjustable position on the rotary member. Upon loosening such bolts, the cutter bar 94 as carried on its holder 101 may be adjusted circumferentially of the rotatable member 93 by a rack and worm gear arrangement 104, as best shown in Fig. 11. That is, the worm gear, as shown, is mounted upon a shaft 105 carried in bearings as at 106-107 formed on the inner face of the member 101, the shaft being adapted to be turned by applying a socket wrench to its end portion 105'. The rack 104' with which the worm gear engages is of arcuate shape and may be secured as by screws, as indicated, within an arcuate cavity 109 formed in the surface of the rotatable member 93. It will be apparent that the adjustment of the cutter bar 94 circumferentially by this arrangement will serve to variably displace the line of perforations formed by this bar with respect to the lines of perforations formed by the bars 95-96. Thus, when the speed of the webs is altered to form bag tubes of different lengths, the position of the bar 94 may be quickly adjusted so that the amount of the "step" between the lines of perforation at the middle of the web and the lines at the sides of the web (see lines 36, Fig. 28) may be readjusted to maintain the desired step, notwithstanding the more rapid or less rapid movement of the webs. As shown in Fig. 12, a graduated scale 108 may be fixed on the rotatable member 93 so that with an accompanying pointer 108' mounted on one of the lugs 102, the operator may readily determine when the cutter bar 94 is in proper position of adjustment circumferentially. That is, the gradations on the scale 108 may correspond to the different desired bag lengths. As best shown in Figs. 11 and 11a, the cutter bars may be formed with a series of slots as at 110, extending circumferentially of the rotatable member 93 and in which bolts or screws 110' are positioned to secure the cutter bar to its holder. The holder may be formed with an outwardly projecting and longitudinally extending flange 111 adapted to receive a series of screws 112 for adjusting each portion of the blade or bar circumferentially, upon loosening of the bolts 110'. The cutting edge of the blade may be adjusted radially and held in its desired position by a series of set screws as at 113 located along between the edge of the blade or bar and the carrier 101 therefor. The active edge of the cutter bar 94 may be dulled or rounded off for a suitable distance as at 94' at each of its ends to avoid formation of perforations at the regions on the webs which are to be ultimately cut apart by the cutter 75.

The other two cutter bars 95 and 96 may be adjustably mounted in a manner similar to the mounting of the bar 94, except that it is unnec-

essary to adjust these circumferentially of the rotatable member 93. Instead, in order to accommodate bags of different widths, they are made adjustable in directions axially of the rotary member 93. This is accomplished by providing the member 93 with longitudinally extending slots as at 114 for receiving bolts 115 which clamp lugs 116 on the blade holders, in position upon the rotatable member. The blade holders for the cutter bars 95, 96 may be provided on their inside surfaces with a small key or bar 117 adapted to be received in a slot as at 118 (Figs. 11 and 12a) extending throughout the length of the rotatable member 93, this key and slot arrangement permitting the holders for cutter bars 95, 96 to be normally applied at the proper circumferential position and there held against circumferential movement while being adjusted endwise and bolted in place.

As shown in Figs. 3-10 inclusive, two glue applicators are illustrated generally at 130, 131, but a description of one will suffice, namely 130, since the construction and operation of the other applicator 131 may be identical therewith. Accordingly, the glue applicator 130 includes a back-up roller 132 under which the web W2 is fed, and a co-acting, rotary glue applicator 134, along which are mounted printing pads 135, Figs. 3 and 4, for printing on the web a transverse glue pattern of the desired configuration, such for example as is illustrated at 40 in Fig. 28. The glue applicator 134 is so driven as to rotate once for each bag length, and the printing pads 135 are so positioned radially as to engage the paper web W2 as it passes under the roller 132.

Glue is applied to the printing pads 135 from a bath 136 thereof, contained in a glue pan 137, into which dips a glue pick-up roll 138 driven in the direction of the arrow thereon, this roll rotating first against a doctor roll 139 and thence against a transfer roll 140, the latter for transferring the glue to the glue pads 135 of the applicator 134. (If desired the doctor roll may be rotated step-by-step through a conventional ratchet and pawl drive means as schematically indicated at 139a in Fig. 26.)

The glue pan 137 is so mounted as to permit of both vertical and horizontal adjustment thereof, the latter transversely of the direction of web feed, and also to permit the pan to be quickly moved out into an accessible position between the perforator units or stands, from which position the pan may be carried endwise out of the machine. To this end the pan is mounted on rolls, as at 141, which travel in grooved guide ways, as at 142, of V-shaped supporting members 143, which are grooved along their lower edges for slideable adjustment along supporting bars 143' having flanges slidably engaging said grooves and also being slotted along their sides to slidably receive complementary ribs 144 of inclined guide members 145 (see Fig. 4).

For providing vertical adjustment of the glue pan and to move it sideways into the above-mentioned accessible position, a hand wheel 146 is mounted on a shaft 147, having secured thereto large pinions 148, 149, and small pinions 148', 149', which mesh, as shown, with rack members 150, 151, and 150', 151' respectively, mounted on the V members 143 and the supporting bars 143', as shown in Fig. 4. By rotating the hand wheel 146 said large and small pinions are rotated and engage their respective cooperating racks whereby the supporting bars 143' will be moved relatively slowly and at an angle somewhat down-

wardly and toward the left as viewed in Fig. 3, while at the same time the V-shaped supporting members 143 are moved in the same direction at a somewhat faster rate, since the latter are moved by pinions larger than those which move the supporting bars 143'. When the racks are moved to the extreme position toward the left (Fig. 3) the glue pan as carried on the members 143 will be quite rigidly supported out in accessible position, where it may be readily carried endwise out of the machine for cleaning or replacement. At this time the supporting members 143' will extend part way out along the members 143 and provide the necessary rigidity to the supporting structure. This mechanism provides a very compact arrangement which may be operated easily and quickly, not only to remove the glue pans for cleaning, but also to permit a sufficient degree of vertical and lateral adjustment thereof, if desired.

The perforator and glue applicator assemblies include, in addition to the perforator and glue applicator mechanisms, a pair of driven pull rolls, 152 and 153, over which paper web W2 is fed, and a similar pair of driven pull rolls 154, 155 over which the paper web W1 is fed. These rolls are driven from a power-driven shaft 156 (Figs. 3, 5) through beveled gears 157, shaft 158 and beveled gears 159, one of which latter is keyed to shaft 160, driving a shaft 161 through a disengageable clutch mechanism 162. Keyed to shaft 161 is a pinion 163 engaging gears 164 and 165, the latter keyed to shafts 166 and 167, respectively, on which are mounted rolls 155 and 153, respectively. As shown in Fig. 3, roll 154 is driven from roll 155 through intermeshing gears 164, 170 thereon; roll 152 being driven in similar fashion from roll 153 through similar intermeshing gears 165, 171 thereon, respectively.

As hereinabove indicated and as shown in Figs. 24 and 25, the main pull rolls of the machine are located at 71 following the tube forming unit, and these main pull rolls ordinarily serve to determine the speed of travel of the webs, but in view of the long lengths of the webs in passing through the machine over numerous rolls and the varying tensions which may occur in the individual webs, it has been found desirable to provide the pull rolls as at 152-155 for each web individually at locations ahead of the perforators, to act as auxiliary pull rolls when needed. That is, the web W1, for example, in passing over the rolls 154 and 155 follows an S-shaped path and upon the occurrence of any substantial tension in this particular web, its frictional engagement with these rolls will cause the necessary forward tension to be applied to the web at this region to insure against any likelihood of breakage of the web as might occur if all of the necessary forward tension for advancing the web had to be applied by the main pull rolls 71. On the other hand, if the main pull rolls are advancing the web in a manner such that there is very little tension therein at the region of its S-shaped path over the rolls 154-155, then these rolls will not have sufficient frictional engagement with the web to cause it to be advanced excessively and become loose at any point on its way to the main pull rolls.

The rotary glue applicators 134 and 172, of the gluing mechanisms 130 and 131, receive driving power from driven shaft 173, which drives through bevel gears 174, a vertical shaft 175, which is linked to shaft 176 through a clutch mechanism 177. Shaft 176, in turn, drives shafts

178 and 179 through beveled gears 180 and 181, respectively. Keyed to shafts 178 and 179, respectively, are driving pinions 184, 185, which mesh with gears 186, 187, the latter being carried by the shafts 188, 189, on which the rotary glue applicators 172 and 134 are respectively mounted. Gear 187 drives, through a train of gears at 190 (Fig. 4) the series of glue rolls 138, 139 and 140. In similar fashion, pinion 186 drives through a train of gears similar to 190 (but not shown), the glue applicator rolls of the lower gluing mechanism 131.

Clutch 162 is actuatable, rocking fashion, by a hand lever 194, Fig. 3, for disengaging the drive from the pull rolls 152 to 155, inclusive. Similarly, clutch 177 is actuatable by a hand lever 195, Figs. 3 and 5, to disconnect the drive from the gluing mechanisms 130 and 131 and also from the perforator 90.

20 The rotary perforator drum 93 is driven from pinion 185 through the concentric intermediate gears 196 and 197, Fig. 7, mounted on shaft 198 and gear 199, the latter mounted on shaft 200 of the rotary perforator drum 93. For disconnecting the perforator drum 93 independently of the drive above described, gear 196 is loosely mounted on the hub of gear 197 in the manner illustrated in Fig. 7, and is provided with a resiliently retractable pin 201 which engages a hole drilled in the face of gear 197.

The gear 199 is of annular form mounted upon a central hub-like portion 199' and adapted to be secured thereon against rotation, as by set screws, as indicated. As shown in Fig. 8, the gear 35 199 may be provided with a graduated dial around adjacent its periphery, for cooperating with a pointer mounted on the hub portion 199' so that when the set screws are loosened, the angular position of the hub and rotor 93 may be

40 adjusted with respect to gear 199, thereby to adjust the angular position of the perforator knives with respect to the remainder of the drive mechanism, and with respect to the angular positions of the perforating knives at the other perforator units. This enables adjustment of the

45 positions of the perforator knives on each rotatable perforator member, as necessary to accommodate the machine for the manufacture of bag tubes of various different lengths. That is, 50 by thus adjusting the angular position of the knives on each rotatable member as at 93, one may in effect adjust the length of the path of the web from the point of perforation to the point where all the webs are assembled, with the several lines of perforation on each in the desired relationship, which occurs in the region of the longitudinal glue applicator 66 on unit D of the machine. As hereinafter explained, minor adjustment of the relative positions of the perforations on the assembled webs may be made by adjusting the relative positions of the rollers 64

60 on the unit D, but when the length of bag to be made is altered substantially, it will be necessary to angularly adjust the rotatable members as at 65 93 by the use of the dial, as shown in Fig. 8. At the same time it will also be necessary to adjust the drive gear 187 for the glue applicator roll 134 (Fig. 10). Accordingly, the gear 187 is mounted upon a hub and adjustable thereon with an indicator dial similar to that shown in Fig. 8 for the cutter rotor. These dials may be graduated in terms of bag tube lengths.

Referring to Figs. 14 to 23 inclusive for a detailed description of the "pagoda" assembly 75 shown generally at D in Fig. 1a, and referring

more particularly, for the moment, to Figs. 14 to 18 inclusive, the assembly comprises a box-like lower supporting frame 225, on which are mounted a pair of spaced-apart uprights 226, 227, having flanged faces 228, 229, disposed in inclined relation to the vertical, as viewed in side elevation (Fig. 14). Along the flanged faces are mounted in spaced-apart, horizontal relation, a series of five rollers 230 to 234 inclusive, each of these rollers being rotatably mounted, as by interposed roller or ball bearings (not shown) on a fixed shaft, as at 236, which extends at its opposite ends respectively through appropriate bores as at 237, 238 of shaft supporting blocks 239, 240, and is secured thereto by means of nuts threaded onto the shaft ends, as at 241. These supporting blocks are of the configuration shown more particularly in Fig. 18, each being supported at its inner end in a guide block 242 of substantially U-shaped cross section, Fig. 18, this block being provided along its opposed inner side walls with a pair of opposed ribs 243, 244, engaging slotted recesses 245, 246 of the shaft support 239, whereby the latter is slidable along the guide block 242. These guide blocks are mounted on the inclined, flanged frame faces 228, 229, as at 242, 246, Fig. 16, being bolted thereto, as at 247, Fig. 18.

The inner portion of each shaft support 239 is tapped and threaded, as at 248, Fig. 18, for threaded reception of a shaft, as at 249, to one end of which is secured a beveled gear, as at 250, which meshes with an associated beveled gear 251, keyed to a shaft, such as 252, paralleling the roll shaft 236, shaft 252 being journaled through bearing plates as at 253, 254, bolted to the exterior side frames as at 255. Each shaft 252 projects at one end beyond the outer face plate 253, and has keyed to this end, a beveled gear, as at 256, which meshes with an associated beveled gear, as at 257, the latter being journaled in a split bearing 258, mounted on the adjacent bearing plate 253.

It will be observed from the mechanism thus far described, that application of driving power to gear 257 will in turn drive gear 256, meshing therewith, thus driving shaft 252 and gears 251 mounted on the opposite ends thereof, which in turn drive gears 250, meshing therewith, respectively, to drive the threaded shafts 249 secured thereto, thus concurrently to displace the shaft supports 239, 240 along their associated guideways 243, 244 of guide blocks 242, thereby correspondingly to displace shaft 236 and roll 233 mounted thereon. In similar fashion, application of driving power to gear 260, Fig. 16, linked to shaft 261 through gear 262, will displace shaft 263, mounting roll 232, the direction of displacement, i. e., up or down in Fig. 16, depending on the direction in which gear 260 is driven. The object of this arrangement is to provide a means of adjusting the spacings between the rolls 230 to 234, either individually, in pairs or in groups as desired, and for purposes explained below.

In order to show how this is accomplished, reference will now be had to Figs. 19 to 21 inclusive in conjunction with Figs. 14 to 18 inclusive. In Figs. 19-21 inclusive, gears 258, 256, and shaft 252 serve to adjust roll 233, as in Fig. 16, while gears 260, 262 and shaft 261 similarly adjust roll 232. In similar fashion gears 265, 266 and shaft 267 adjust roll 230; gears 268, 269 and shaft 270 adjust roll 231; while gears 271, 272 and shaft 273 adjust roll 234.

Now it will be observed that gears 265, 268, 260,

258 and 271 are mounted in axial alignment, each being provided with a relatively large axial bore, at its base, as at 274, terminating at its upper end in a relatively small keyway 275. Extending axially through the bores of all of these gears is a shaft 276, journaled at its opposite ends to bearing supports 277, 278, carried by the frame 226. Mounted on shaft 276, adjacent the successive gears 265, 268, etc., respectively, are a series of splined collars 285 to 289 inclusive, which are relatively so disposed on the shaft that as the shaft is axially displaced, up or down, only one or a selected group of the splined collars, at a time, will engage the keyway 275 of the adjacent gear or gears. Thus with the shaft positioned as shown in Fig. 19, collars 288 and 289 engage, respectively, the keyways of gears 258 and 271, while the remaining collars 285, 286 and 287 are disengaged from their associated gears 265, 268 and 260, respectively. Accordingly, should the shaft 276 be rotated while in this position of axial displacement, shafts 252 and 273 would be driven, concurrently to displace rolls 233 and 234, in the manner above described, and either up or down, depending on the direction in which shaft 276 is rotated. On the other hand, with shaft 276 axially shifted to the position shown in Fig. 20, spline 285 is in engagement with gear 265, while all of the remaining splines are disengaged from their respective gears. Finally, with shaft 276 shifted to the position of Fig. 21, splines 286 and 287 are respectively engaged with gears 268 and 260, while the remainder are disengaged. The purpose of the particular sequence of spline engagements illustrated in Figs. 19 to 21 inclusive will be explained below, but it will be understood, of course, that by appropriately positioning the collars along the shaft, any other desired sequence of engagement may be secured, such, for example, as selective individual engagement of each collar with its associated gear for individually adjusting any of the various guide rolls 230 to 234 inclusive in the manner aforesaid.

For purposes of adjusting shaft 276 up or down, the shaft is provided on its lower end with a rack portion 290, of alternating peripheral ribs and slots, Fig. 14, engaged in all positions of shaft rotation by a pinion 291, linked (Fig. 15) through beveled gears 291a to a shaft 292, in turn geared through shafts 292a and 292b to a hand wheel for purposes of manually adjusting shaft 276 to provide gear engagement as desired. For thereafter rotating the shaft 276 to adjust a guide roll as aforesaid, there is mounted on this shaft, a bevel gear 295, journaled to a split bearing 296, mounted on one of the bearing plates 253. Gear 295 is axially bored and slotted to provide a keyway engaged by the splined collar 288 and shaft 276 for all axial displacement thereof, as illustrated in Figs. 19 to 21 inclusive, collar 288 being of sufficient length to accomplish this, as shown in the drawings. Referring to Figs. 14 and 17, gear 295 meshes with a bevel gear 300 keyed to a shaft 301, which is also geared to a hand wheel for manually rotating the same thereby to adjust a guide roll or rolls as aforesaid. The above-mentioned hand wheels may be located adjacent the forward part of the machine as at 292', 301' (Fig. 1b), convenient for the operator when standing in position to watch the separated finished bag tubes being discharged.

The purpose of the selective roll spacing ad-

justments above described is to vary the extent by which the perforation lines of the successive bag plies overlie one another, as at 310, 311, 312, Fig. 32; or the extent to which these perforation lines are spaced with respect to the bag cutoff line $x-x$, Fig. 29. As above explained, the bag plies 10 and 11 are identically perforated in superimposed relation, the same being true of bag plies 12 and 13, while ply 14 is perforated as a single ply. It is for this reason that in the selective gear engaging mechanism of Figs. 19 to 21 inclusive, gears 258 and 271 are arranged to be concurrently engaged, thereby concurrently to adjust the upper guide rolls 233, 234, carrying webs 10 and 11, Fig. 14; and likewise arranged concurrently to engage gears 260 and 268, for concurrently adjusting guide rolls 231 and 232, carrying the paper webs 12 and 13; but individually to engage gear 265 for adjusting the remaining guide roll 230, which carries the paper web 14.

It will be noted, referring to Fig. 14, that after the paper webs 10 to 14 inclusive are fed over their respective rolls 234 to 230 inclusive of the "pagoda," the webs pass thence downwardly along an inclined path, as at 313, and such as to superimpose the successive webs as they pass over the successive guide rolls, until all five plies are superimposed beneath the lowermost roll 230, as at 314, the thus superimposed bag plies being laterally disposed to provide progressively overlapping lateral edges, as at 67 of Fig. 29. At this point the bag plies are fed through the glue applicator mechanism, shown generally at 66, Fig. 14; which applies to the undersides of the overlapped web edges 67, Fig. 29, glue lines as indicated at 67a thereof.

The glue applicator mechanism 66 is illustrated in detail in Figs. 15, 22 and 23, referring to which, it comprises a glue pot 317, mounted, as at 318, on a base plate 319, the under side of which has formed thereon, undercut, beveled guides, as at 320, Fig. 22, which slidably engage complementary beveled guides 321, formed on the upper face of a supporting plate 322, carried by the frame member 323. For slidably adjusting the glue pot 317 and supporting base member 319 along the supporting member 322, there is secured to the base plate 319, a projecting arm 324 which terminates in an internally threaded sleeve member 325, through which extends, in threaded engagement, a positioning screw 326 journaled through a bracket member 327, mounted upon the frame member 323, and terminating in a hand wheel 328, for manually positioning the glue pot as desired.

Mounted within the glue pot 317 on a shaft 329, journaled through bearings 330 in the opposite end walls of the pot, are a series of glue applicator discs 331, which are individually adjustable along shaft 329 by means of adjusting screws threaded through the hubs thereof, as at 332. These glue applicator discs dip into a bath 333 of glue, and are rotatable as explained below, to apply glue lines as at 67a, Fig. 29, to the undersides of the overlapped edges 67 of the paper webs 10 to 14 inclusive.

Secured to one end of shaft 329 is a hubbed disc 335, having formed therein an annular slot of T-shaped cross section, as at 336, Fig. 23, within which is positioned the head of a bolt 337, which bolt passes through a longitudinal bore in a wide faced gear 338, mounted on the hub of disc 335. Bolt 337 has threaded onto its projecting end, a nut 339, which, upon being tightened,

locks the gear 338 against the disc member 335, but which, upon being loosened, permits of rotating the gear on the disc hub without moving the disc member and shaft 329 keyed thereto, or vice versa, and for purposes hereinafter explained.

Gear 338 is provided with helical teeth 340, meshing with the teeth of a narrow-faced gear 341, which latter is splined to a shaft 342, journaled through bearing support 343, 344 of a supporting member 345, mounted on the base plate 319. Straddling gear 341 is a yoke member 346 which is drilled and tapped for threaded reception of a shaft 347, which is likewise journaled through the supports 343, 344, and has secured thereto an adjusting knob 348. One end of shaft 342 has pin-connected thereto, as at 349, a sleeve member 350 which telescopes a splined shaft 351, the latter being journaled through a bearing 352, mounted on the frame 323, and terminating in a beveled gear 353, meshing with gear 354 of a driven shaft 355.

In the operation of the glue applicator, driving power applied to shaft 355 drives through gears 353, 354, the shafts 351, 342 to drive gear 341, which in turn drives gear 340 and with the shaft 329 to rotate the glue applicator discs, against the paper webs as explained. Referring to Fig. 22, in order to prevent the glue applicator discs 331 from applying continuous glue lines to the paper webs, including the overlapped, perforated bag ends 310 to 312, Fig. 32, each disc is provided with a peripheral slot, as at 356, which is adjusted to span the region of the bag end perforations 310 to 312 inclusive, Fig. 22. This adjustment is accomplished by means of the gear and disc assembly 335, 337, in conjunction with the intermeshing gear and adjustable knob assembly 339, 341, 348. For approximate adjustment of the disc slots 356 with reference to the bag end perforations, nut 339 is loosened and the glue applicator shaft 329 manually rotated to approximately the appropriate position, nut 339 being thereupon tightened. A fine adjustment, which may be made during running operation of the machine, is thereupon obtained by manual rotation of knob 348, which displaces gear 341 along the helical teeth of gear 338, (Fig. 15) by virtue of the internally threaded yoke 346 straddling gear 341, this displacement of gear 341 along the teeth of gear 338 providing rotary adjustment of the latter, irrespective of whether the machine is running or not. For preventing transfer of excess glue by the discs 331 to the paper webs, forked wipers, such as 360, straddle the disc, in the indicated direction of rotation thereof for removing excess glue picked up from the glue bath 333. The superimposed paper webs are fed through the glue applicator under guide rolls 361, 362, which span the point at which the glue applicator discs 331 contact the paper webs, thereby to assure the application of continuous glue lines, except for the interval provided by the disc slots 356.

Referring now to Figs. 1a, 2 and 2a, the superimposed paper webs 68, having glue lines 67, Fig. 29, applied along the underside of the overlapping longitudinal edges, as aforesaid, are fed from the glue applicator 66, into the tubing device E. As the paper webs are fed through this tubing device, the lateral edges thereof are gradually curled inwardly, until the overlapping web edges along one side are superimposed on the overlapping lateral edges on the other side

of the superimposed webs, thereby forming a continuous paper tube, such as is illustrated in Fig. 30, wherein the edges carrying the glue lines 67 have now been turned face upwardly, and the opposite edges of the various plies 11 to 14 inclusive, superimposed thereon respectively, to form a series of paper tubes, one within another, the opposite edges of each such tube being glued together in overlapping relation along one of the glue lines 67.

Referring now to Figs. 1b, 2a, 24, 25 and 25a, the so formed multiwall continuous bag tube passes out of the exit end of the tubing device between a series of driven pull rolls 71, which flatten and feed the bag tube thence through a slitter 12, comprising driven upper and lower rotatable assemblies 378, 379, the upper assembly having mounted thereon, adjacent the opposite ends thereof, respectively, a pair of slitter knives as at 380, for slitting all plies of the bag tube, in the manner illustrated at 73, 74, Figs. 25 and 30. As will be apparent from Figs. 24 and 25, each of the slitter knives, which may have an arcuate serrated edge of a length corresponding to the desired length of the slits 73—74 (Fig. 30), is mounted in a knife holder 380', which in turn may be bolted at various angular positions about a hub portion as at 380a in order that the slitting knives will operate in properly timed relation to other parts of the machine, to form the slits at the proper position across the ends of the lines of perforation (as shown in Figs. 30 and 31). The hub portions 380a, as will be apparent from Fig. 25, may also be adjusted axially of a rotating shaft which carries the same, such adjustment being necessary to provide for bag tubes of different widths. This shaft may also include a coupling 380b, bolted together through slotted bolt holes to permit the angular position of both slitting knives to be concurrently adjusted. The serrated edges of the slitting knives pass down through all of the paper webs as shown in Fig. 25a, and the lower rotatable assembly 379 may include axially adjustable roller portions having peripheral slots at 379' to receive the serrated slitters. The manner in which the slitter may be driven and its timing controlled during operation of the machine, will be further described hereinafter, it being understood that in changing bag lengths, it will ordinarily be necessary to take off the slitting knives and substitute others and to approximately adjust the angular positions thereof by the coupling device 380b, and then after the machine is running, fine adjustment of the longitudinal position of the slits in the webs may be accomplished as explained below in connection with the description of the drive mechanism for the machine.

After the webs pass through the slitting mechanism, they may pass through a pair of small auxiliary pull rollers as at 381, which are driven as hereinafter explained with a peripheral speed such as to keep the paper flat and insure its advance into the subsequent cutting mechanism at the same speed as the speed of travel through the main pull rollers 71.

The bag tube next passes through the cutter 75, for cutting and separating the bag tube into bag lengths, as illustrated in Fig. 31. The cutter 75 comprises a stationary cutter bar 382, mounted on a supporting frame 383, and a cooperating driven rotary cutter drum 384, mounting near its opposite ends, respectively, a pair of cutter bars, as at 385, for cutting the bag tube in the manner

illustrated at 76, 77, Fig. 31. These cutter bars, as indicated, may have a suitable bolt and slot connection with the drum to be adjustable along the drum for bags of various widths. The cutter drum is mounted on a shaft 386, which is journaled through appropriate bearing members, mounted on a supporting structure, as indicated at 387, 388 of Fig. 25.

Also mounted on the entry and exit sides of the cutter, are pairs of driven rolls 78 and 79, the lower rolls 389 and 390 of which, are mounted on shafts journaled to the frame members 387, 388, and the upper rolls 391, 392 of which are mounted on shafts journaled respectively, as at 393, 394, to rock levers, such as 395, 396, the latter being keyed to shafts 397, 398, journaled to bracket members, such as 399, 400, which in turn are mounted on the frame members 387, 388. The rock levers 395, 396, at each end of the cutter drum 384 have secured thereto respectively cam rollers, as at 402, 403, which ride upon cams, such as 404, mounted respectively at each end of the cutter drum 384, and secured thereto by means of clamping screws passing through adjusting slots 25 of the cams, as at 405. The opposite ends of the rock levers 395, 396, are resiliently secured to the frame members 387, 388, by means of springs, such as 406, 407, one end of each of which, is secured to a frame member 387, 388, and the opposite end of each of which is secured to a rock lever, as at 408, 409. The cutter drum cams 404, are of circular configuration, concentric with the drum shaft, except for a cut-away portion 410, disposed at a circumferential position corresponding generally to that of the rotary cutter bars 385.

The operation is such that the circular portion of the cam 404, by engagement with the rock lever cam rolls 402, 403, normally holds the upper entry and exit rolls 391, 392, sufficiently displaced from 40 the associated lower rolls 389, 390, that substantially no drive is applied by the entry and exit roll pairs 389, 391 and 390, 392, to the paper tube 411 passing therebetween. However, just after the cutting edge of the rotary cutter bars 385 engages the stationary cutter bar 382 to sever the bag tube 411 into bag lengths as above described, the cam 404 disengages the cam rolls 402, 403, by virtue of the cut-away portion 410 thereof, thus permitting the rock levers 395, 396 to rotate respectively counterclockwise and clockwise sufficiently, under the action of the hold-down springs 406, 407, as to cause the upper entry and exit rolls 391, 392 to engage the interposed paper tube 411 and apply drive thereto by coaction with the lower rolls 389, 390. Now as above stated, the exit rolls 79 are driven at a slightly higher speed than the entry rolls 78, whereby, as a result of the momentary drive applied by the entry and exit rolls to the paper tube, the tube at the instant following cutting is pulled apart along the perforation lines 80, Fig. 31, thereby to separate the tube into bag lengths as there illustrated. It should be emphasized in this connection that the entry rolls 78 operate at the same surface speed as the preceding driven rolls in the tuber machine, while the exit rolls 79 operate at a higher speed.

Referring to Figs. 26 and 27, which show diagrammatically the overall drive for the machine, this drive is so arranged, as explained below, as to 70 drive at constant speed, the perforator and glue applicator rolls of units A, B, C and D, and also the slitter 12 and the cutter 75. In conjunction therewith the drive is also arranged to drive at an adjustable speed, the various pull rolls for the 75 paper webs, such, for example, as the pull rolls

34, 33, 42, 44 and 59 of the perforator and glue applicator units A, B, C, and the pull rolls 71, 78, 79 at the slitter and cutter units 72, 75. All of the pull rolls (excepting at 79) are, however, driven at the same surface speed, for any driven adjustment of the drive therefor. The reason for this is to permit of adjusting as desired, the bag length to be produced on the machine. This is accomplished quite simply by appropriately adjusting the speed at which the web pull rolls are driven in relation to the constant speed at which the perforator, glue applicator and slitter and cutters are driven.

The adjustable speed at which the paper web pull rolls are driven is accomplished by interposing between the driven shafts for the various pull rolls and a constant-speed prime mover driving source, a differential gearing arrangement, mounted in a rotatable housing, which latter is driven through a gear and intermeshing worm, the worm of which is in turn driven from the constant-speed source through a variable speed drive, such as any well known P. I. V. type of drive, the latter for adjusting the speed at which the worm is driven, and thereby through the differential gearing mechanism referred to, the speed at which the web pull rolls are driven.

In Figs. 26 and 27, the constant-speed prime mover source comprises the motor 425, which drives through pulleys 426, 427, and interlinking V-belts 428, a shaft 429 to which is keyed a gear 430. Gear 430 drives through gear 431, meshing therewith, a gear 433, keyed to a shaft 434. Shaft 434, in turn, drives through beveled gears 435, the main drive shaft 173, above referred to, from which the perforator and glue applicator rolls of units A, B, C and D are driven, as above described in connection with the preceding drawings.

In Figs. 26 and 27 the various driven components are given the same numerical designations as in the preceding drawings, with the exception of the perforator and glue applicator unit C, to which prime marks are added to the numerals, since only one of these units, namely, unit C, is illustrated in Figs. 26 and 27, the remaining units A and B not being included in the drawing, because driven in identically the same manner as unit C.

Thus in Figs. 26 and 27, shaft 173, driven at constant speed as explained, drives through beveled gears 174 and interposed clutch 177, the drive shaft 176 for the perforator and glue applicator units C, shaft 176, in turn, driving the perforator roll 60' and the glue applicator rolls 134', 138', 139' and 140', in the manner above explained in detail, and hence requiring no further description. Likewise, at the pagoda D, the main drive shaft 173 drives through beveled gears 436, shaft 355, which, in turn, drives the glue applicator discs 331 through the interposed gearing in the manner above described in detail, and hence requiring no further description here. Thus, the various perforator and glue applicator rolls of units A, B, C and D are driven at constant speed, from the main drive shaft 173.

In Fig. 27, motor 425 has keyed to its shaft 431, a gear 438, which meshes with a larger gear 439, the latter mounted on a shaft 440. Keyed to shaft 440 is a gear 441, of a differential unit, shown generally at 442, which includes a rotatably mounted housing 443, within which gear 441 is mounted, this gear meshing with a smaller gear 444, mounted on a shaft 445 journaled to the housing 443 as shown. Gear 444, in turn,

meshes with another small gear 446, mounted on a shaft 447, likewise journaled to the housing 443. Meshing with gear 446 is a larger gear 448, mounted on a shaft 449 journaled axially through the housing. Shaft 449 drives through beveled gears 450 a shaft 451, which, in turn, drives through beveled gears 452 a shaft 453. Shaft 453, in turn, drives through beveled gears 454, the rotary cutter drum 384 of the cutter 75, and also drives through beveled gears 455, shaft 456 and beveled gears 457, the rotary slitter blades 380 of the slitter unit 72.

Ignoring for the moment the presence of the interposed differential 442, it will thus be observed that the slitter and cutter units, 72 and 75, are driven at constant speed from motor 425 through the differential 442, and over shafts 449, 451 and 453.

Now the purpose of the interposed differential 442 is merely to adjust the registry of the slitter and cutter units in relation to the perforator units A, B and C. To this end the housing 443 of the differential 442 is rotatably mounted, and is provided thereon with a gear 460 with which meshes a worm 470, mounted on a shaft 471, connected by gears 472 to a shaft 473, terminating in a hand wheel 474 located near the "pagoda" adjustment hand wheels (Fig. 1b). By manipulating the hand wheel 474 the housing 443 of the differential 442 may thus be rotated, clockwise or counterclockwise as desired, to adjust the registry of the slitting and cutting operations in appropriate relation to the perforating and transverse gluing operations of units A, B and C, and this irrespective of whether or not the machine is running or not. Aside from this registry adjustment, the differential 442 has no effect on the speed at which shaft 453 is driven from motor 425.

For driving the pull rolls for the paper webs, there is keyed to shaft 434, driven from motor 425 as aforesaid, a second gear 475 which drives through an intermediate gear 476, a gear 477 keyed to a shaft 478. The gear 475 may be a "change gear" adapted to be replaced by gears of other sizes when the bag length is to be altered substantially, the gear 476 being an idler, the axis of which is carried on a swingable arm for adjustment of the position of the idler to accommodate various change gears. Secured to the opposite end of the shaft 478 is a gear 479, which in turn drives a gear 480, mounted on a shaft 481 which is journaled through the housing 482 of a differential gear 483. Differential gear 483 is similar to that at 442, previously described, in that it contains within the housing a gear 484 keyed to shaft 481, gear 484 meshing with a smaller gear 485, mounted on a shaft journaled in the housing, as at 486, and in turn meshing with a second small gear 487, also journaled in the housing as at 488, gear 487 in turn meshing with a larger gear 489 mounted on a shaft 490 journaled through the housing in alignment with shaft 481.

Shaft 490 drives through beveled gears 491, shaft 156, which latter drives through beveled gears 159 and interposed clutch 162, the pull rolls 59 of the perforator C, and similarly drives the pull roll in perforators A and B. Shaft 490 also drives through the various intermeshed gears shown generally at 492, the various pull rolls 71 at the exit side of the tuber, the shaft 493 of the last pull roll in assembly 71 also driving through beveled gears 494, shaft 495 and beveled gears 496, the pull rolls 78 on the entry side

of the cutter 75, and drives through shaft 495, beveled gears 497 and intermeshing gears at 498, the pull rolls 79 on the exit side of the cutter. It will thus be seen that all of the web pull rolls are driven from motor 425 through the differential 483, all of the pull rolls being thus driven at the same surface speed except pull rolls 79 on the exit side of the cutter, which latter, by virtue of the step-up ratio pinions, are driven at a higher speed, and for reasons above explained.

The gearing arrangement of differential 483, above-described, would result in a fixed and constant speed drive for the pull rolls. But for adjusting the speed up or down, as required, and in conformity with a desired bag length to be produced, the housing 482 for the differential is rotatably mounted on the axis of shafts 481, 490, and has mounted thereon a worm gear 500, driven by a worm 501 mounted on a shaft 502. Shaft 502 is driven from motor 425 as follows: The above described driven gear 431, driven from the motor by gear 430, is mounted on a shaft 503 which drives, through gears 504, a shaft 505 which drives, through a variable-speed driving unit 506 (such as a P. I. V. type of drive) a shaft 507, which in turn drives, through beveled gears 508, a shaft 509. Shaft 509 in turn drives shaft 502 through beveled gears 510 and a differential gearing arrangement shown generally at 511. (A hand wheel for slowly turning over the machine by hand is shown at 504').

With the arrangement described, shaft 505 is driven at constant speed from shaft 503, in turn to drive shaft 509 at a speed which is adjustable up or down and to a limited degree desired in relation to that of shaft 505, by virtue of the interposed P. I. V. drive 506, the speed adjustment being effected by manipulation of the adjusting knob 512 on the P. I. V. drive. The P. I. V. drive requires no description herein, since its construction and operation, in various embodiments, is well known.

Neglecting, for the moment, the action of differential 511, it will be seen that the speed of shaft 502 will depend on the aforesaid speed adjustment of shaft 509. And since shaft 502 is continuously driven in the manner described, the housing 482 of differential 483 will be driven by the worm gears 500, 501, at a speed determined by that of shaft 502. Consequently the main pull roll drive shaft 490 will be driven at a speed comprising the difference between the constant speed at which the input drive shaft 481 of the differential 482 is driven, and the adjustable speed at which the housing 482 is driven as aforesaid. In this way, the speed at which the paper web pull rolls are driven may be increased or decreased, as desired, within limits as determined by the range of adjustment of the P. I. V. drive 506, as compared to the constant speed at which the perforator, slitter and cutter units are driven, thereby to form bag tubes of adjustable length within said limits. For substantial differences in bag length, the above-mentioned change gears at 475 may be used, and for fine adjustments while the machine is running, the P. I. V. drive may be adjusted.

Now the differential gear 511, interposed between shaft 509 and 502, provides a registry adjusting component or "compensator" for appropriately adjusting the area of perforating, slitting and cutting in relation to printed matter appearing on the exterior web of the formed multiweb tube. Thus, assume for example that the outer web is printed with any of the various

legends and pictorial representations that the uses of the finished bags may require. In the absence of a suitable registry adjusting device, the multi-ply bag tube might well be perforated, slitted and cut into bag lengths within the areas of the printed matter, and this condition may gradually come about while the machine is running.

In order to provide a registry adjusting mechanism to eliminate this objection, the differential gear 511 comprises a conventional differential gearing assembly 512 through which shaft 502 is driven from shaft 509. The gearing 512 is mounted with a rotatable housing 513, having mounted thereon a worm gear 514 driven by a worm 515, the latter mounted on a shaft 516 which is normally stationary, but which may be driven clockwise or counterclockwise to provide registry adjustment as follows. Shaft 505, driven at constant speed as above described, drives, through beveled gears 517, a shaft 518, on which is mounted a beveled gear 519. Mounted on shaft 516 and on opposite sides, respectively, of the driven gear 519, are a pair of beveled gears 520 and 521, which mesh with gear 519 but normally idle on shaft 516. Interposed between the idle gears 520, 521, is a double-throw clutch mechanism 522, actuatable by a hand lever 523 to throw either gear 520 or 521 into driving engagement with shaft 516, preferably at short intervals, thereby to drive the shaft clockwise or counterclockwise, as desired, and so long as the clutch is thus engaged. The resulting rotation of shaft 516 by driving the differential housing 513 through the worm gearing 514, 515, increases or decreases the speed of the paper web pull rolls until the desired registry is obtained between the printed matter on the bag tubing and the areas of perforating, slitting and cutting, after which the clutch 522 is disengaged by restoring the hand lever 523 to its mid-position. As shown in Fig. 1b this lever may be located near the other hand wheels 474, 292' and 301' for convenient manipulation by the operator while watching the discharge of the tube lengths.

What is claimed and desired to be patented is:

1. In a machine for manufacturing multi-ply stepped-end paper bag tubes, the combination comprising a tube-former for folding a plurality of superposed paper webs as drawn therethrough into a multiply tube, pull rolls adjacent the exit of said tube-former for pulling the formed tube therethrough, a plurality of rotary perforators in advance of said tube-former for perforating said webs at bag length intervals along lines which will be in stepped relationship on the several webs when assembled, a plurality of glue applicators for then applying glue respectively to the surfaces of individual webs which are to face other superposed webs and along adjacent the lines of perforation thereon, a plurality of rollers around which the webs pass individually in travelling from said applicators to said tube-former, said rollers being arranged in spaced parallel positions with their axes substantially along a single plane, whereby a web passes around each and then into superposed relation along such plane with the other webs which pass around others of said rollers respectively, and thence into said tube-former, a remote control mechanism common to all said rollers for adjusting the spacing thereof to vary the lengths of the paths of travel of said webs and consequently the stepping of the perfora-

tions thereon, and a remotely controlled clutch means for bringing said mechanism into operative relationship with said rollers selectively for such adjustment thereof while the machine is running.

2. In a multi-ply bag tubing machine, including a tube-former, a plurality of parallel rollers around which a plurality of paper webs pass individually, said rollers being positioned to direct the webs therefrom into superposed relation and into the tube-former, interconnected screw means at opposite ends of each roller for concurrently adjusting the spacing of both ends of the roller with respect to others of the rollers while maintaining the parallel relation thereof, remotely controllable gear mechanism common to all of said rollers for operating said screw means, and remotely controllable clutch means for bringing such mechanism into operative relationship with said screw means for various rollers selectively.

3. In a machine for manufacturing multi-ply stepped-end paper bag tubes, the combination comprising a tube-former for folding a plurality of the superposed paper webs as drawn therethrough into a multi-ply tube, pull rolls adjacent the exit of said tube-former for pulling the formed tube therethrough, means in advance of said tube-former for transversely perforating said webs at bag length intervals along lines which will be in stepped relation on the several webs when assembled and also glue applicators in advance of said tube-former for applying glue to one surface of each web which is to face another superposed web, a plurality of parallel rollers contacting the opposite web surfaces and around which rollers the perforated webs then pass individually, said rollers being positioned to direct the webs therefrom into superposed glued-together relation and into said tube-former, interconnected means at the ends of each of said rollers for concurrently adjusting the spacing of both ends of the roller with respect to others of said rollers while maintaining the parallel relation thereof to thereby vary the lengths of the paths of travel of the perforated webs respectively and consequently the stepping of the perforations thereon when superposed.

4. In a machine for manufacturing multi-ply stepped-end paper bag tubes, the combination comprising a horizontally positioned tube-former for folding a plurality of superposed paper webs as slidably drawn therethrough into a multi-ply tube, pull rolls adjacent the exit of said tube-former for pulling the formed tube therethrough, means in advance of said tube-former for transversely perforating said webs at bag length intervals along lines which will be in stepped relation on the several webs when assembled and also glue applicators in advance of said tube-former for applying glue to a surface of each individual web which is to face another superposed web, a plurality of parallel rollers all substantially tangent to a single plane and around which the webs thereafter pass individually, said rollers being positioned to direct the webs therefrom into superposed glued-together relation along said plane and down to the entrance of said tube-former without abrupt deflection after superposing of the webs and at an angle of from about 40 to 50 degrees to the horizontal position of the tube-former.

5. In a machine for manufacturing multi-ply stepped-end paper bag tubes, the combination comprising a tube-former for folding a plurality

of paper webs as drawn therethrough into a multi-ply tube, pull rolls adjacent the exit of said tube-former for pulling the formed tube therethrough, means in advance of said tube-former for guiding the webs in laterally stepped relation and for transversely perforating same at bag length intervals along lines which will be in stepped relation longitudinally of the webs when assembled and also glue applicators for applying glue to a surface of each individual web which is to face another superposed web, a plurality of parallel rollers around which the webs then pass individually into superposed glued-together relation and into the tube-former, a glue applicator with discs for applying glue respectively to the laterally stepped edges of the webs when brought into said superposed relation, and means for synchronously driving said discs and the perforating means, said discs being formed with gaps to omit the application of glue at the perforations.

6. In a multi-ply stepped-end paper bag tubing machine having rotary mechanisms for perforating at bag intervals, interpasting and superimposing a plurality of paper webs, a tube-former and pull rollers for drawing the webs through the machine, the combination comprising a drive for driving the perforating and interpasting mechanisms one revolution per bag length, a drive for the pull rollers which is variable according to the desired bag tube length, a main differential gearing assembly forming a part of the latter drive, also a variable gearing assembly for adjusting the speed of one of the drive components of said differential gearing assembly, another differential gearing assembly interposed between said drive component and the variable gearing assembly, and a shiftable gearing means for driving one of the drive components of the latter differential gearing assembly in either direction momentarily to control the main differential gearing assembly to increase or decrease the pull roller speed as compared with the perforating speed, thereby to permit the adjustment of the longitudinal positions of perforations on the webs as compared with any other markings thereon.

7. In a multi-ply paper bag tubing machine having rotary mechanism for perforating part way across a plurality of paper webs at bag length intervals, and a tube-former followed by pull rolls for drawing therefrom the perforated webs as a formed flattened tube, the combination comprising a pair of rotary slitters for longitudinally slitting the tube at bag length intervals in the region of the perforations after the tube has passed through said pull rolls, a rotary cutter and separating mechanism subsequent to said slitters for transversely cutting across the unperforated portions of the tube and for separating the bag lengths as perforated and thus cut, a further pull roll between said slitters and said latter mechanism, means for driving said pull rolls synchronously at variable speed, drive means for driving said slitters, and said cutter and separating mechanism at the rate of one revolution per bag length, the latter drive means including differential gearing to enable adjustment of the registry of the slits and cuts with respect to the perforations while the machine is running.

8. In a multi-ply stepped-end paper bag tubing machine having a plurality of roll stands from which paper webs are supplied, and a tube-former followed by pull rolls for drawing the webs through the machine, the combination comprising a plurality of units each containing a

perforator and a glue applicator, said units being located between said stands and the tube-former, said units being constructed and arranged to perforate and apply glue transversely of the webs at bag length intervals and being spaced apart with walkways therebetween, each unit having a rotary perforator adjacent to and accessible at one of said walkways and a glue applicator adjacent to and accessible at another of said walkways, guides for guiding paper webs from said stands along beneath the respective units, thence upwardly, rearwardly through the perforators and then the glue applicators, thence further upwardly and forwardly and to a point of assembly of the webs in superposed relation and into the tube-former, said applicators being positioned to apply the glue to the web surfaces which face rearwardly during such further upward travel.

9. In a multi-ply paper bag tubing machine having a plurality of roll stands from which paper webs are supplied, and a tube-former followed by pull rolls for drawing the webs through the machine, the combination comprising a plurality of units each containing a perforator, a glue applicator and auxiliary pull roll means, said units being located between said stands and the tube-former, said units being constructed and arranged to perforate and apply glue transversely of the webs at bag length intervals and being spaced apart with walkways therebetween, the perforator, glue applicator, and auxiliary pull roll means of each unit, all being accessible from said walkways, guides for guiding paper webs away from said stands respectively, thence upwardly into and rearwardly through the perforators and then through the gluing means of said units respectively, thence further upwardly and forwardly, and a web assembly unit interposed between the tube-former and the last of the above-mentioned units and in spaced relation thereto, said assembly unit including a plurality of parallel rollers over which the perforated paper webs pass individually, said rollers being positioned to direct the webs therefrom into superposed relation and downwardly into said tube-former.

10. In a multi-ply paper bag tubing machine, the combination comprising a plurality of rotary perforators, a plurality of rotary glue applicators for applying glue at bag length intervals to surfaces of webs which are to face other webs when the webs are superposed, a tube-former, rollers for guiding a plurality of webs respectively through said perforators past said applicators, and thence into assembled superposed relation and into said tube-former, pull rolls for pulling the webs through the machine, drive means for driving said pull rolls at a variable speed depending upon the desired bag length between perforations, other drive means for driving said perforators and glue applicators in synchronism and with one revolution per bag length, and the latter drive means having interposed therein driving and driven parts which are relatively adjustable angularly, for adjusting the angular positions about their axes of each of the perforators and glue applicators individually as compared with the positions of the other perforators and applicators, whereby when the pull roll speed is varied for different bag lengths, a predetermined relationship between the perforations and glue areas on the several webs may be maintained.

11. In a multi-ply paper bag tubing machine, the combination comprising a plurality of rotary

perforators, a tube-former, rollers for guiding a plurality of webs respectively through said perforators and thereafter into assembled superposed relation and into said tube-former, pull rolls for pulling the webs through the machine, drive means for driving the pull rolls at a variable speed depending upon the desired bag length between perforations, other drive means for driving said perforators in synchronism and with one revolution per bag length, and the latter drive means having interposed therein driving and driven parts which are relatively adjustable angularly, for adjusting the angular positions about their axes of each of the perforators individually as compared with the positions of the other perforators, whereby when the pull roll speed is varied for different bag lengths, a predetermined relationship between the perforations on the several webs may be maintained.

12. In a multi-ply bag tube forming machine, the combination comprising a plurality of rotary perforators for perforating webs respectively at bag length intervals part way across each, a tube-former, rollers for guiding the webs through said perforators respectively, thence in assembled superposed relation through said tube-former, main pull rolls for pulling the webs through the machine, two additional pairs of pull rolls, a rotary cutter between said pairs for cutting the unperforated portions of the multi-ply tube at bag lengths, and mechanism operating in synchronism with said rotary cutter for normally holding said pairs of pull rolls in inactive position, but acting to bring same into gripping relationship with the tube just after each operation of the cutter, the last of said pairs of pull rolls operating at a higher peripheral speed than the first pair, thereby to cause separation of the bag lengths along the perforations after the cutting operation.

13. A machine for forming multi-ply stepped-end bag tubes, characterized by having in combination a plurality of rotary perforators for perforating webs at intervals, each perforator including a plurality of knives constructed and positioned to perforate part way across a web and to leave unweakened areas, a tube-former, guide means for directing the webs through said perforators and thence in superposed relation into said tube-former with the lines of perforation thereon in stepped relation, rotary slitter, cutter and separating means subsequent to the tube former for longitudinally slitting the formed multi-ply tube at the ends of the lines of perforation, for cutting across the unweakened areas and for separating the formed multi-ply tube into stepped-end tube portions, drive means for rotating said perforators, slitter and cutter in synchronism at a rate corresponding to the number of such tube portions being formed, pull rolls for drawing the webs and formed tube through the machine, and other drive means for rotating said pull rolls at a rate variable according to the desired length of said tube portions.

14. A machine for forming multi-ply stepped-end bag tubes, characterized by having in combination a plurality of rotary perforator units respectively for perforating different webs at intervals, applicator means adjacent each of said units for applying localized areas of adhesive to the individual webs adjacent the lines of perforation, drive means each separately disconnectible from a source of power and individual to each unit for driving same and its accompanying applicator means, a tube-former, guide means for directing

the webs along different paths through said units respectively and past said applicators, thence into superposed adhered relation and thence into said tube former, with the lines of perforation which were formed in the respective perforating units on different webs in stepped relation, but at least one of said units having guide means for directing a pair of webs superposed and in contact therethrough for simultaneous perforation followed by guide means for separating such pair while passing the applicator means and for then directing such pair into the aforesaid adhered relation with the other webs which were perforated in other units independently of such pair.
